METHOD AND APPARATUS FOR
REFRIGERATION

Edward Rice, Jr., New York, N. Y.

Original application July 14, 1930, Serial No.
467,999. Divided and this application August
25, 1934, Serial No. 741,464

10 Claims. (Cl. 62—91.5)

This application is a division of my application for patent filed July 14, 1930, Serial Number 467,999.

This invention relates to improvements in methods and means for refrigerating by use of solid refrigerants, such as water ice (solid H_2O), and carbon dioxide ice (solid CO_2).

The invention described and claimed herein resides in a novel means for maintaining a solid refrigerant in continuous contact, or in uniform conductive relation, with a substantially vertical portion of a solid metallic heat conductor which absorbs heat from the refrigerated space or material on extended metallic surfaces and transmits this heat to the adjacent surfaces of the solid refrigerant. This is accomplished by providing a supporting base for the refrigerant which is inclined toward a side wall of the refrigerant containing space formed by a portion of the metallic conductor, thereby causing the refrigerant to slide down continuously by gravity against the conductor as the refrigerant melts, and to keep the heat absorbing surfaces of the conductor chilled as long as any of the refrigerant remains. Provision is also made for continuously draining away the meltage of the refrigerant so that, when solid refrigerants such as water ice are used, the ice will not float off the inclined base and lose contact with the conductor wall. An object of the invention is to provide a method of refrigerating by means of solid refrigerants whereby the effective refrigerating temperatures are to a substantial degree independent of the volume of the refrigerant, and to this latter end, the invention contemplates the provision of a method for materially increasing the refrigerating efficiency of relatively small quantities of a solid refrigerant.

More specifically, an important object of the invention is the provision of a method of refrigeration by the use of a solid refrigerant which will produce effective refrigerating temperatures in the refrigerating chamber more closely approximating the melting or subliming temperature of the ice than the heretofore known methods, and which will maintain such temperatures even when the mass of ice has been reduced to relatively small dimensions.

Still another object of the invention is the provision of a method of refrigerating by use of solid refrigerants which will permit a rapid acceleration in the rate of ice meltage or sublimation irrespective of the volume of the refrigerant when the temperatures in the refrigerated area are increased.

A still further object of the invention is to provide a method of refrigeration by means of a solid refrigerant which will permit the refrigeration of practically any desired space whether occupied with a gas (including air), liquid, solid or a combination thereof without actual contact of the refrigerant with the contents of the space whereby when required the refrigerant may be entirely divorced from the refrigerated area.

A still further object of the invention is the provision of refrigerating apparatus for use with a solid refrigerant in which the principal heat transfer to the refrigerant takes place from the refrigerated space or mass to a conductor of high thermal conductivity and extended surface, and thence conductively to a relatively small surface of the refrigerant through a section of the conductor sufficiently large to transmit the required amount of heat for maintaining a predetermined effective refrigerating temperature.

Still more specifically, as regards the use of solid H_2O and similar solid refrigerants of relatively high melting point, an object of the invention is to provide a novel method of refrigeration which will produce effective refrigerating temperatures more closely approximating the melting temperature of the ice than has heretofore been possible, and will maintain such temperatures even after the volume of the ice has been reduced to relatively small amounts.

A further object of the invention is the production of a refrigerating unit of such character that it may be employed either in household and stationary refrigerators or in the refrigeration of railway cars, motor truck bodies, or other transportation units.

Still another object of the invention is to provide simple and relatively inexpensive refrigerating units of a character adapted for use in household and other refrigerators employing solid H_2O whereby my invention may be readily available for that class of refrigeration.

The invention further resides in certain novel and advantageous structural features and details and in specific embodiments representing various applications thereof to different classes of refrigeration, all as hereinafter set forth and illustrated in the attached drawings, in which:

Figure 1 is a diagrammatic sectional view illustrating an embodiment of my invention as applied to household refrigerators and similar class of refrigeration;

Fig. 28 is a diagrammatic vertical sectional view of a railway car showing another method of refrigeration in accordance with my invention.

Water ice or solid H_2O is more widely used than any other form of refrigerant. One of the principal drawbacks in the prior methods of using this refrigerant or, in fact, any solid refrigerant is that although any given mass of the refrigerant, no matter how small, has a fixed refrigerating value; yet the smaller the mass becomes, the slower its refrigerating action becomes also. This is due to the fact that the heat is usually either entirely or almost entirely brought to the ice convectively either by air or a liquid, and the amount of heat taken up by the refrigerant, other things being equal, depends directly on the

amount of the effective surface contact between the refrigerant and the circulating fluid. Obviously as the ice melts, the surface area becomes less and the refrigerating action slower. In the construction of refrigerating apparatus, this feature, heretofore, has been given no consideration, and no effort has been made to compensate for the rapid decrease in efficiency as the refrigerant loses volume and surface area. As a result, a great deal of ice is constantly being used with very indifferent or inferior results.

One reason that the mechanical household refrigerator has progressed so rapidly is because the ordinary water ice refrigerator cannot maintain satisfactory refrigeration unless it is continually serviced and kept practically full of ice at all times. For the same reason, a large and growing field for refrigeration of foodstuffs in motor transportation has avoided the use of water ice and other solid refrigerants. Practically the only method attempted to improve the efficiency of water ice as a refrigerant has been the use of salt, a method of limited application which apparently cannot be greatly extended.

I have discovered that the principal obstacles to the efficient use of water ice and other solid refrigerants can be largely overcome if the heat from the space or material to be refrigerated is picked up by comparatively extended surfaces of a metal heat conductor, such as copper, aluminum or iron, and transferred through a substantial cross section of the metal conductor directly to a surface of the body of ice with which the metal conductor is either in immediate contact or in suitable conductive relation. I have found that by this method, the ice can be melted at practically a constant rate, thus providing a constant effective refrigerating temperature practically independent of the volume of the refrigerant, and even with extremely small masses of the latter. I have found also that the refrigerant can be melted at an almost inconceivable rate when large amounts of heat are passed over the extended metal surfaces. With a sufficient cross section of the conductor metal, as small as thirty square inches of contact surface with the refrigerant will suffice to melt enough water ice to keep a good household refrigerator below 50° F. even on the top shelf in the warmest weather; and after the doors have been opened as long as three minutes, this refrigerator will return to its original low temperature within twenty minutes or one-half hour. It is essential in the practice of my invention that the solid refrigerant be maintained in conductive relation with a substantial metal conductor having a suitably extended surface area in the refrigerated space.

While the invention is of great importance in conjunction with the use of water ice, it is also of great value in the use of all other solid refrigerants, such as solid carbon dioxide and frozen brine. The apparatus embodying my invention need vary only slightly to meet the requirements of the particular kind of refrigerant and the type of refrigeration required. If, for example, refrigerating temperatures around 35° to 45° F. are desired and water ice is to be used by reason of its cheapness and availability, then a relatively large amount of extended conductor or fin surface will be required because of the small temperature differential between the water ice and the temperature required; while the same temperatures can be secured by use of solid carbon dioxide with considerably less surface area by reason of the fact that with solid

carbon dioxide the conductor can be chilled to almost any temperature required down to say minus 50° F., and accordingly a relatively large temperature differential be maintained between 5 the conductor and the refrigerated space. Obviously if temperatures are wanted near or below the melting point of water ice, then some other solid refrigerant may be used with a sufficiently low melting or subliming point that the conductor 10 can be put at a temperature affording the differential required to maintain the refrigeration wanted. Frozen brine may be used especially when put up in small and easily handled units in liquid-tight metal containers. The heat 15 transferred from the conductor to the solid brine through the metal container, however, is not as constant and controllable as in the direct contact of water ice with the conductor or the contact of carbon dioxide ice with the conductor 20 through a known amount of conducting resistance, as hereinafter more specifically set forth. However, as the frozen brine can be provided with a melting point practically anywhere between 32° F. and considerably below zero and 25 has now come into more common use and also is comparatively cheap, it is apparent that it will have a limited use as a solid refrigerant means in my method of refrigeration. Of course, frozen brine directly in solid state can be used 30 in the same way as water ice or carbon dioxide ice by permitting the melted brine to drain off.

With reference to the drawings, in which I have illustrated various specific applications of my invention to different types and classes of refrigeration, and with particular reference to Figs. 1 and 4, the reference numeral 1 may indicate the outer shell or case of a household refrigerator of well known type, this refrigerator including a central vertical baffle wall 2 and a compartment 3 in one of the upper corners for reception of the refrigerant. In accordance with the prior practice, refrigeration is obtained in this type of refrigerator by the convective action of air currents circulated as indicated by the 40 arrows downwardly over and around the ice in the compartment 3, downwardly through an aperture 4 provided in the base of this compartment, under the baffle 2, and upwardly in the main refrigerating chamber 5. In accordance with my invention, I provide within the 50 chamber 3 shelves 6, 6, for reception of the refrigerant, which shelves incline inwardly towards a conductor 7 provided with a plurality of projecting fins 8, as most clearly shown in Fig. 4. Inclination of the shelves 6 insures retention of the face of the ice masses 9 supported on these shelves in close contact with the conductor 7, which latter is located as shown in relation to the baffle wall 2 so as to provide between the 60 vertically arranged fins, the conductor 7, and the baffle vertical passages through which the convective currents circulate downwardly over the extended surface of the conductor. As the ice melts, the latter feeds by gravity up against the conductor, thereby maintaining continuous contact between one face of the ice masses and the conductor. The ice meltage passes out through the usual drain 11, and the air after circulating over the conductor and its fins comes in contact 70 with this melted ice water, which removes the undesirable odors from the air, and then passes from the refrigerator. With apparatus of this type, it is possible to maintain relatively low temperatures within the casing even when the 75 ice has been reduced to a very small volume.

In Fig. 2 I have illustrated in perspective a refrigerating unit made in accordance with my invention and of a type adapted for insertion in household refrigerators of the usual type. This unit comprises a rectangular casing 12 open at top and bottom and having in the interior a plurality of vertical fins 13. At the lower end of the forward wall is a depending apron 14 which at its bottom edge turns upwardly to form a channel adapted to receive the drip of the melting ice, and from this channel extends downwardly a drain pipe 15. The unit also comprises an inclined shelf 16 which provides for maintaining continuous contact between the refrigerant and the inner vertical wall 17 of the unit. Preferably this wall 17 of the unit and the fins 13 are made of copper, aluminum or other metal having a relatively high conductivity factor.

As shown in Fig. 3, this unit may be secured 20 in an upper corner of the refrigerator case 18, it being noted that the forward wall 19 of the unit terminates at the top at a point below the upper end of the fins 13, whereas the rear wall 17 extends to the top of the fins which, in the present instance, abut the upper or top wall of the casing. In this manner, a circulation of the convective air currents is set up downwardly through the unit between the fins 13 and over the face of the rear conductor wall 17. The meltage passes through apertures at the inner or lower end of the shelf 16 and falls downwardly into the channel apron 14 whereby the air currents after passing over the surfaces of the conductor pass through the dripping water, which latter acts to remove the refrigerator odors from the air. In order to prevent excessive condensation moisture and possible dripping of this moisture from the shelf 16 on the stored food, the latter preferably is provided with a layer 30 of suitable insulating material 21.

It will be noted that each of the devices described above meets the essential requirements of my invention. In each instance, a conductor is provided for conducting heat from the space to be refrigerated to the refrigerant. This conductor is so formed, with fins in the present instance, as to present to the space to be refrigerated a relatively extended area, and its cross sectional dimensions are entirely adequate to 45 transmit heat in required amount picked up on the said extended surfaces to the surface or surfaces of the ice with which the conductor is in direct contact. Since in the use of water ice this direct conductive contact between the conductor 50 and the ice is essential, provision is made in the form of the inclined ice-supporting shelves to maintain the refrigerant in constant contact with the conductor. With this arrangement, the heat 55 may be carried to the refrigerant at a rate insuring maintenance of a predetermined adequate effective refrigerating temperature in the refrigerated space even when the ice has been reduced to an extremely small volume. With this device, therefore, it is possible to maintain adequate refrigerating temperatures with relatively infrequent servicings, the refrigerant being adequate even after the volume is greatly reduced from the maximum capacity of the refrigerator.

In Fig. 6, I have illustrated a form of fin conductor suitable for use in the practice of my invention and made of a heavy copper conductor plate 35 bent at right angles, to which are soldered or welded thin copper fins 36 on both the vertical and horizontal walls. At the junction of 60 65 70 75 80 85 90 95

these two walls an outlet pipe 37 is provided for elimination of the ice meltage. This type of refrigerating unit is adapted for use in refrigerators with water ice where it is desirable to maintain two different temperatures—a comparatively low temperature in a small compartment directly beneath the ice pan where the heat is taken up by the horizontal fins, and a higher temperature in a comparatively large compartment in which the convection currents pass over the vertical fins. The lower wall of the unit in assembly is inclined towards the vertical wall so that the ice tends to maintain a position in the angle with adjoining faces in contact with the vertical and bottom walls respectively.

Fig. 7 shows a type of conductor of primary value in connection with carbon dioxide ice. This unit comprises an angular casting 38 of aluminum with copper fins 39. The ice-supporting wall is slightly inclined towards the juncture with the upright wall, and in the angle outlets 41 are provided for elimination of the gases of sublimation. The principal heat transfer in this instance takes place through the thin copper fins, down the upright side of the casting to the bottom or ice-supporting wall. Interposed between the solid carbon dioxide and this lower wall is a suitably selected conductor resistance 42, and the ice is also surrounded by suitable insulation 43.

In Figs. 8 to 12, inclusive, I have illustrated various types of fin conductors which have been found suitable in the practice of my invention. The form of conductor illustrated in Fig. 8 is one that can be conveniently used for household refrigeration purposes, this being made up from a number of bent copper sheets 45 soldered together at the points designated 46 so as to present a substantially flat conductor plate surface for contact with the solid refrigerant and a considerably extended fin surface for contact with the convection currents.

Fig. 9 shows a similar construction in which the outer ends 47 of the projecting fin portions are turned inwardly toward each other so as to afford the same amount of contact surface in a more restricted space.

Fig. 10 shows a more efficient type of conductor in which thin copper fins 48 are soldered or welded to a heavy copper conductor plate 49.

Fig. 11 shows a still more efficient but more expensive form of conductor consisting of a solid aluminum plate 51 with thin copper fins 52 secured to the aluminum plate by casting the latter on the fins.

Fig. 12 shows an all-aluminum fin conductor formed of a single casting.

Figs. 13 and 14 illustrate a desirable form of water cooler adapted for use with water ice. The refrigerator comprises a copper tank 71, one side of which forms an abutment for the refrigerant which is maintained in contact therewith by gravity through the medium of an inclined support 72. From this refrigerant-abutted wall fins 73 project into the interior of the tank, which as illustrated has an inlet pipe 74 preferably emptying directly above the said fins. The arrows indicate the direction of the convection currents set up within the tank which carries the contained liquid over the surfaces of the fin conductor wall.

This is a very efficient form of liquid cooler in which the temperature of the liquid is reduced very rapidly, and by extending the insulating casing 75 rearwardly, the latter can be given any capacity required for the solid refrigerant to maintain the refrigerating action over very ex-

tended periods of time. As the ice melts, it will be understood that it feeds continuously by gravity towards and against the conductor plate of the tank 71.

In Figs. 15 and 16, I have illustrated a large table or cabinet type of refrigerator adapted for use either with CO_2 ice or water ice and in which provision is made for obtaining in the three separate compartments three different temperatures, when CO_2 ice is used, or of two temperatures when water ice is employed. This refrigerator consists of an outer insulated casing 111 having in the top a chamber for a refrigerant, the opposite sides and the bottom of which are constituted by a channel-shaped conductor 112. The side walls of this conductor are provided with outwardly projecting fins 113, and the bottom wall is slightly elevated towards the center to create a tendency of the solid refrigerant to move by gravity towards the vertical fin walls. Access to this refrigerating chamber is had through a removable cover 114. Three refrigerating chambers are provided numbered 115, 116 and 117, respectively, the chamber 116 being located directly below the refrigerant chamber. Baffles 118 in the chambers 115 and 117 extend vertically and preferably in contact with the outer edges of the fins 113 whereby a convective circulation is set up in which the air moves downwardly between the fins and against the side walls of the conductor. The chamber 116 is separated from the other chambers by insulating walls 119, and in one or both of the chambers 115 a valve 120, which may be operated manually or automatically from a suitable thermostatic actuator, is provided for controlling the movement of the convection currents downwardly past the walls and fins of the conductor. Where carbon dioxide ice is used, the refrigerant is surrounded in the refrigerating chamber on four sides and the top by suitable insulation 121, while the ice is separated from the bottom of the conductor by means of suitable conductor resistance 122. The temperature in the chamber 116 is controlled by the thickness and character of the conductor resistance, whereas the temperatures in the compartments 115 and 117 are controlled not only by the conductor resistance, but also by the thickness and character of the insulation 121, and may be still further controlled by manipulation of the valve 120.

Figs. 17 and 18 illustrate this same apparatus as used with water ice, it being noted that in this case the insulation 121 and the conductor resistance 122 are removed, the water ice being maintained in contact with the side walls of the conductor by reason of the inclination of the bottom wall after a manner previously set forth.

Fig. 19 illustrates a portable shipping container for refrigerating purposes for use with either water ice or solid carbon dioxide, and in which provision is made for maintaining different temperatures in the refrigerating chambers. The construction is essentially the same as that illustrated in Figs. 15 and 16, one of the refrigerating chambers being provided with a valve 125 in the major convection passage whereby movement of the air past the conductor may be suitably controlled.

In Figs. 20 and 21, I have illustrated a desirable form of cabinet refrigerated in accordance with my invention and adapted for the rapid cooling of milk or other beverages. The insulated cabinet 175 encloses a chamber 176 adapted for reception of the refrigerant. One wall of this

chamber 176 is constituted by a conductor 177, this conductor having on its outer face a plurality of vertically arranged sets of inclined fins 178. Shelves 179 are provided in the interior of 5 the chamber 176 for support of the refrigerant, and these shelves are inclined downwardly towards the conductor wall 177 so that the ice as it melts will feed by gravity downwardly towards the conductor and remain continuously in contact therewith over a substantial surface area of 10 the refrigerant. From the chamber 176 the ice meltage escapes to the atmosphere through a port 181. The fins 178 project into a chamber 182, in the open top of which is established a 15 receptacle 183 having in the bottom a discharge opening or openings 184 located immediately over the tops of the upper bank of fins 178. From the bottom of the chamber a duct 185 extends outwardly to a spigot 186, through which the 20 contents of the chamber 182 may be withdrawn. Milk or other beverage poured into the container 183 trickles through the openings 184 onto the fins 178 and flows downwardly over the lower banks of fins in a tortuous path afforded by the 25 relative angular arrangement of the said banks. Refrigeration of the beverage is immediate, and it may be withdrawn immediately from the tube 186 in a cooled condition. The refrigeration also may take place by filling the chamber 182 and 30 permitting the liquid to pass over the surface of the conductor and of the fins 178 by convection. It will be noted that the casing 175 also encloses a chamber 187 the bottom of which may 35 constitute a storage space for containers 188 for the particular beverage in connection with which the apparatus is used.

In Fig. 22, I have illustrated a well known form of store show case refrigerated in accordance with my invention. In the rear of the case is a 40 chamber 191 for the refrigerant, this refrigerant resting upon an inclined base 192 which effects a continuous contact between the refrigerant and a conductor plate 193. This plate has fins 194 projecting into the storage space of the show 45 case, and a baffle 195 and false bottom 196 in the case afford a passage for directing the air currents circulated by convection through the case, as indicated by the arrows.

Figs. 23 and 24 illustrate a method of refrigerating large truck bodies or the like in accordance with my invention. The body is indicated by the reference numeral 212, doors 213 being provided affording access to the interior. At the top and at one side of the body a chamber 214 is 50 provided for the refrigerant, this chamber having in the present instance side walls 215 formed of copper, aluminum or other suitable material having a high conductivity factor. These conductor plates 215 are provided with fins 216 which project into the interior chamber of the truck, and the truck interior is also provided with suitable baffle plates or false walls 217 which form channels for conduction currents, as indicated by the arrows, which currents pass downwardly through 55 the fins 216 and over the surfaces of the conductor plates 215 whereby a thorough and rapid refrigeration of the interior of the truck body is effected. It will be noted that the shelves 218 which support the refrigerant are slanted downwardly toward the conductor plates 215 whereby the refrigerant is maintained continuously in contact or in conductive relation with the plates in the manner previously set forth.

Another feature of the construction shown in 75 Fig. 24 is the radiation shield or false top 219

which preferably extends over the entire roof of the body in spaced relation to the latter, this shield preferably being made of hard bright metal tending to deflect the heat rays of the same and preventing direct contact of the rays with the top wall of the refrigerated chamber.

In Figs. 25 and 26, a refrigerating system is illustrated suitable for small truck bodies and the like and adapted for refrigeration with practically any type of solid refrigerant. The body 221 in this instance has a chamber 222 at one end and in the upper portion for reception of the refrigerant, the bottom and front wall of this space being constituted by a suitable angular conductor plate 223, and the said front wall being 10 provided with fins 224 which project into the interior or refrigerated area of the truck. The space directly under the bottom of the conductor plate 223 is enclosed by a partition 225 and constitutes a cold compartment whose temperature 15 may be maintained at a relatively low point. A false wall or baffle 226 is provided in the interior of the body which forms a channel for the circulation of the convection currents, as indicated by the arrows, the circulating air passing downwardly over the upright face of the conductor 223 and between the fins 224. I also may provide in this instance a valve 227 in the air passage whereby the circulation of air may be controlled 20 either manually or by a suitable thermostat, thereby affording a further control of the interior 25 temperature of the truck. Where, as illustrated, a refrigerant such as solid carbon dioxide is employed, this refrigerant will be surrounded by an insulating sleeve 228 and separated from the bottom of the conductor member by a suitable conductor resistance element 229. The temperatures 30 may be controlled by regulating the thickness and character of the conductor resistance and of the insulating sleeve 228. Where water ice 35 is employed, the sleeve 228 and conductor resistance 229 may be eliminated. It will be noted that in this case also I employ on the top of the truck body a suitable radiation shield 231.

Fig. 27 shows a well known type of railway express car well adapted to refrigeration in accordance with my invention. The car body 232 has a dome-like roof 233, and in the interior and depending from the roof 233 is a refrigerating unit, one or more, each consisting of a receptacle 45 for the refrigerant, the sides 234 of which and the bottom 235 are made of a material such as copper or aluminum having a relatively high conductivity factor. The side walls 234 of the conductor are provided with fins 236 which project 50 outwardly into the refrigerated interior of the car, and outwardly of these fins baffle partitions 237 are provided which guide the circulating convection currents downwardly over the surface of the conductor walls 234 and the fins 236. 55 False walls or baffle partitions 238 are also provided for further controlling the circulation of the air, which is substantially as indicated by the arrows. The bottom wall 235 of the refrigerating unit may be protected on the under side 60 by suitable insulation 239 to prevent condensation. When water ice is used, the meltage from the refrigerant may pass through apertures 240 into channels 241 in the bottoms of the channel plates 237, and may be conducted thence to the 65 exterior of the body. In this instance also a radiation shield 242 is provided above the roof of the car.

Fig. 28 shows another arrangement for refrigerating railway cars in which independent re- 75

frigerating units are provided in each of the upper corners of the car, the units being designated by the reference numeral 243 and being constructed in accordance with the principles set forth above. The usual partitions are provided in this instance for controlling the convection currents and for guiding the currents over the conductor surfaces of the refrigerating units.

I claim:

- 10 1. In apparatus for refrigerating with solid refrigerants, the combination with a refrigerant-containing chamber, of a solid thermal conductor of a highly conductive metal extending from said chamber to the space to be refrigerated and presenting to the latter a surface area materially greater than the surface area in contact with the refrigerant body, and means in said chamber for supporting the refrigerant in continuous conductive relation with an upright portion of said conductor, which portion forms a side of said refrigerant-containing chamber.
- 15 2. In apparatus for refrigerating with solid refrigerants, the combination with a solid thermal conductor of a highly conductive metal having an extended surface area exposed in the space to be refrigerated materially exceeding the surface area in contact with the refrigerant body, and means for maintaining the refrigerant in continuous conductive relation with an upright portion of said conductor, which portion forms a side of the refrigerant-containing space.
- 20 3. In a refrigerator, the combination with a solid thermal conductor of a highly conductive metal having surface areas exposed to the refrigerated chamber materially in excess of the surface area in contact with the refrigerant body, and a support for a solid refrigerant adapted gravitationally to maintain the refrigerant in continuous conductive relation with an upright portion of said conductor, which portion forms a side of the refrigerant-containing space.
- 25 4. A refrigerating unit comprising a solid thermal conductor of a highly conductive metal having an extended surface area in the space to be refrigerated materially exceeding the surface area in contact with the refrigerant body, and a refrigerant support inclined toward the said conductor whereby a solid refrigerant on said support will gravitate towards the said conductor.
- 30 5. A refrigerating unit for use with solid refrigerants comprising a conductor having an extended surface in the space to be refrigerated and presenting to the latter a surface area materially greater than the surface area in contact with the refrigerant body, a support for the

refrigerant slanting toward the conductor whereby a solid refrigerant is held by gravity in contact with the conductor, and means for conducting away from said unit the meltage of the refrigerant.

6. A refrigerating unit comprising a thermal conductor having an extended surface area, partition means embracing said surface and forming an open-ended duct through which a fluid may circulate in contact with said surface, and a refrigerant support inclined towards the said conductor whereby a solid refrigerant on said support will gravitate towards the said conductor.

7. A refrigerating unit comprising a thermal conductor having an extended surface area, partition means embracing said surface and forming an open-ended duct through which a fluid may circulate in contact with said surface, and a refrigerant support inclined towards the said conductor whereby a solid refrigerant on said support will gravitate towards the said conductor, the said support being formed by a portion of the said conductor.

8. A refrigerating unit comprising a thermal conductor having an extended surface area, partition means embracing said surface and forming an open-ended duct through which a fluid may circulate in contact with said surface, and a refrigerant support inclined towards the said conductor whereby a solid refrigerant on said support will gravitate towards the said conductor, together with means for continuously draining off the meltage of the refrigerant from the lower part of the refrigerant-containing space.

9. In refrigerating apparatus in which a vertical heat-absorbing metal wall is cooled by a solid refrigerant, the method of maintaining the solid refrigerant in continuous conductive relation with said wall, which consists in supporting the solid refrigerant on an inclined base, whereby the refrigerant tends to gravitate against said wall, and continuously draining off the products of dissolution of the solid refrigerant.

10. In refrigerating apparatus, cooled by a solid refrigerant such as water ice, brine ice, or solid carbon dioxide, in which a substantially vertical metallic side wall of the refrigerant-containing space absorbs heat derived from the refrigerated space or material, the combination with means for maintaining the solid refrigerant in continuous contact with said wall, said means including a support for the refrigerant inclined toward the said wall.
